UNITED STATES PATENT OFFICE.

FRANK A. LUNDQUIST, OF CHICAGO, ILLINOIS, ASSIGNOR, BY MESNE ASSIGNMENTS,
TO HENRY S. CONRAD, TRUSTEE.

TELEPHONE EXCHANGE.

Application filed September 30, 1918, Serial No. 256,188. Renewed June 15, 1923.

To all whom it may concern:

Be it known that I, FRANK A. LUNDQUIST, a citizen of the United States of America, and a resident of Chicago, county 5 of Cook, and State of Illinois, have invented certain new and useful Improvements in Telephone Exchanges, of which the following is a specification.

My invention relates to automatic telephone exchanges and has for its object improvements in such exchanges. The line switch, shown in the lower part of the general diagram, has been described in detail in my pending application Serial Number 10 248,104, filed August 3, 1918; and the selector switch, shown in the central part of the diagram, has been described in detail in my pending application Serial Number 15 250,873, filed August 21, 1918. The connector, shown in the upper part of the diagram, will be described herein.

In the drawings hereunto annexed—

Fig. 1 is a side elevation of a connector; Figs. 2, 3 and 4 are sections on lines 2—2, 25 3—3 and 4—4, respectively, of Fig. 1;

Fig. 5 is a partial elevation of some of the apparatus shown in Fig. 1, but from the opposite side;

Fig. 6 is a diagram of two line switches, 30 the one at the left being a calling switch and the one to the right being a called switch;

Fig. 7 is a diagram of the selector;

Fig. 8 is a diagram of the connector; and 35 Fig. 9 is a diagram showing the non-interfering connections between two connectors.

Fig. 6 at the bottom, Fig. 7 in the middle, and Fig. 8 at the top, taken together represent one diagram covering a calling operation.

The frame of the connector is composed of a bottom bar 11, a top bar 12, and end bars 13 and 14.

45 Near the central part of this rectangular frame is a pneumatic motor which consists of a tube 15 arranged to slide on a standard 16 carried in a small frame 17. (Figs. 1, 3, 4 and 5.) Compressed air entering through pipe 18 over the top of the standard 16 causes the tube 15 to rise.

Another pneumatic motor consists of a

tube 19 which slides on a horizontal standard 20 secured to the end bar 13. In this case the standard is hollow and the air enters through the pipe 21. The frame 17 is secured to the outer end of motor 19 so that when motor 19 is actuated it carries motor 15 toward the right, as shown in Fig. 1. A small wheel 22, secured to the frame 60 17 and running on a track 23, supports the weight of motor 15 and associated parts so that this weight does not put a strain on motor 19.

Supported in a bracket 24 on the bar 11 65 is a gear 25 which meshes with a rack 26 on motor 19. On the same spindle with the gear 25 is a case 27 (Fig. 1) which contains a clock spring acting upon gear 25 in a direction to hold the motor normally to 70 the left as seen in Fig. 1.

Supported on the bracket 24 is a magnet 28 whose armature 29 is connected to an escape lever 30 acting upon an escape wheel 31 secured to gear 25. If impulses flow 75 through the magnet 28 at a time when compressed air is admitted to the motor 19, the motor 19 will move the motor 15 step by step to the right as these parts appear in Fig. 1, or to the left as they appear in 80 Fig. 5.

On the motor 15 are racks 32 which engage gears 33 secured to a sleeve 34. The sleeve 34 is mounted to rotate in the frame 17 and to slide upon the square part of a 85 shaft 35 which extends between and is supported by the bars 13 and 14. Supported on the bar 12 is a magnet 36 whose armature 37 is connected to an escape lever 38 operating upon an escape wheel 39 secured 90 to shaft 35. If impulses flow through magnet 36 at a time when compressed air is admitted to the motor 15, the motor 15 will move upward step by step.

Supported at a convenient place near 95 magnet 36 is a small pneumatic motor 40. (Figs. 2 and 4.) A spring 41 acts to hold the motor 40 in normal position when not actuated by the admission of compressed air. Another spring 42 secured to the armature 37 bears against the head of the motor 40. The spring 42 has a slight initial tension acting to retract armature 37, which tension is increased when the motor is 100

moved from normal position by compressed air.

Secured to the shaft 35 is a wheel 43 which has teeth equal in number to the teeth 5 of wheel 39, and supported at 44 is a pawl 45 adapted to catch in the teeth of wheel 43 and hold shaft 35 in an advanced position after it has been moved from normal position. The pawl 45 has an extension 46 which bears 10 against a collar 47 on motor 40. When the motor 40 is in its normal position the pawl 45 is held from engagement with wheel 43, but when said motor has moved, said pawl falls into engagement with said wheel.

15 On the top of motor 19 is a ratchet bar 48, and pivoted at 49 (Fig. 4) is a pawl 50 adapted to engage ratchet 48 and hold motor in advanced position when moved by compressed air. An extension 51 of the pawl 50 rests on collar 47. When motor 40 is in normal position, the pawl 50 is held away from ratchet 48, but the pawl falls into engagement with the ratchet when the motor 40 is actuated.

20 25 Pivoted on pin 52 (Fig. 4) is another pawl 53 adapted to engage ratchet 48. An extension 54 of pawl 53 projects upward and is engaged by an arm 55 secured on shaft 35. When shaft 35 is in normal position, 30 pawl 53 is held from engagement with ratchet 48, but when the shaft 35 is moved by an upward movement of motor 15, the pawl 53 falls into engagement with ratchet 48.

35 40 45 Pivoted at 56 in the lower right hand corner of Fig. 1 is a disk 57 having ratchet teeth therein. Adjacent thereto is a motor 58 arranged to act upon a lever 59 pivoted at 60. A spring 61 acts to normally hold the lever 59 in the position shown. Pivoted at 62 on lever 59 is a pawl 63 which has an arm normally engaging a pin 64 to hold the pawl 63 from engagement with the teeth in disk 57. When motor 58 lifts lever 59, pawl 63 turns on its pivot to engage the teeth of disk 57, and when motor 58 falls back the force of spring 61 acting on lever 59 advances disk 57 one step.

50 55 60 Pivoted at 65 is a catch 66 arranged to engage teeth on disk 57 and hold it in its advanced position when moved by pawl 63. Connected to an arm on the catch 66 is a rod 67 which extends to and is connected to a wing 68 on the frame 17. When the motor 19 is in its normal position the catch 66 is held free from disk 57, but as soon as the motor 19 has advanced one step the catch 66 drops to engagement with disk 57 and is in a position to act as a holding pawl.

65 60 Supported near the disk 57 is a valve 69, and pivoted at 70 is a lever 71 which has one arm engaging said valve and another arm with a cam 72 arranged to be engaged by an arm 73 secured to the disk 57. The valve 69 is of the self closing kind (like a check

valve), and when the disk 57 is in either its first or third position the valve is closed. But when the disk is in its intermediate position the arm 73 engages cam 72 to move lever 71 so as to open valve 69.

70

On the disk 57 are certain insulated wipers, and supported by a plate 74 are certain insulated contact strips. These parts correspond to the well known side switch and will be described in connection with the circuits 75 to be given later.

75

Supported at a convenient place near the parts just described are two pairs of contact springs which are normally in the position shown in Fig. 1. A piece of insulation 75 carried by the lever 59 shifts these springs to their alternative position whenever the motor 58 lifts said lever. These will be further described in connection with the circuits. 80

85

Supported on the bar 12 is a relay 76, and adjacent to the relay is a valve casing 77 to which compressed air flows from a source through pipe 78. The valve in this casing, which will hereafter be designated by the character applied to the casing, is in the nature of a check valve and is held closed by the pressure of the air in the pipe 78. The stem 79 of the valve extends beyond the casing and is engaged by an adjustable screw 80 in the armature 81 of the relay 76. A spring 82 normally acts to elevate the armature but with a force less than that required to lift the valve from its seat. But when the armature 81 is attracted by an impulse 100 through relay 76, then the attraction plus the force of the spring 82 is sufficient to open the valve. When the circuit is broken through the relay 76, the pressure of air in pipe 78 will close the valve and push armature 81 back against the action of spring 82. But if such break is followed quickly by a remake of the circuit as by the operation of the ordinary calling device at a local station, the armature 81 does not have time to fall 110 back but remains attracted as in the case of an ordinary "slow" relay.

105

On the top of motor 15 is a cross head 83, and on this cross head are arms 84 and 85 which carry insulated wipers 86, 87, 88 and 89. When motor 19 operates, these wipers are moved step by step to the right, as shown in Fig. 1, and when motor 15 operates the wipers are raised step by step. By such movements the wipers are brought into engagement with desired contact points in a rectangular arrangement of such points.

115

On the connector are certain contact springs which will be explained in connection with the circuits. From pipe 78 are branches to the different motors. These will be evident from the drawings and the description to follow.

120

In the diagrams the same battery is shown at a number of different places and is 130

marked X, X' and X² with appropriate plus and minus signs to indicate positive and negative poles. This repetition of the battery is to avoid long and confusing lines drawn upon the diagram. The line switch at the left in Fig. 6 has been advanced from normal position to engagement with an idle trunk leading to the selector in Fig. 7. In the line switch, three motors and one magnet are shown in operated position. At the time a subscriber begins a call these are all in normal position, and the operation of calling will now be described.

The first thing a calling subscriber does is to remove his receiver. This causes a closure, at the local station, of the following circuit: X—resistance R—89—90—91—92—local station—94—95—96—X.

This causes magnet 96 to attract its armature and open valve 97 so as to permit compressed air to flow from a source to the motor 98, which immediately starts upward on a trunk hunting expedition. As soon as the wipers carried by motor 98 come to an idle trunk a new circuit is completed as follows: X—99—100—101—102—103—104—105—105^a—106—107 (which is shown advanced but is in normal position at this time)—108—109—X'.

The impulse thru magnet 100 attracts its armature and causes pawl 110 to engage the teeth on motor 98 and arrest that motor with its wipers in engagement with the found trunk. The armature of magnet 100 also opens valve 111 so as to admit compressed air to motors 112 and 113. Motor 112 is used to prevent the line switch from moving from normal position, but as such movement has occurred before motor 112 acts, this motor accomplishes nothing at this time. Motor 113 throws another pawl 114 into engagement with the motor 98 and also shifts the adjacent contact springs into the position shown in Fig. 6. Shifting these springs connects wire 92 to wiper 117 by way of 91—115—116, and connects wire 93 to wiper 121 by way of 94—119—120. When this is accomplished a circuit is completed for relay 118 of Fig. 7 as follows: X'—118—122—117—116—115—91—92—local station—93—94—119—120—121—123—resistance—X'.

The shifting of the springs by motor 113 breaks for magnet 100 by moving 102 from 103, but immediately remakes by 103 engaging 124 from which the circuit continues—125—126—127—128—129—130. This shift of the springs also breaks the circuit for magnet 96 and this results in air becoming exhausted from motor 98. But pawl 114 is held against the ratchet teeth by motor 113 with sufficient force to prevent motor 98 from falling back when air is exhausted from it.

The circuit just previously described thru

relay 118 causes its armature 131 to close the springs 128—129 in the last circuit given, and also to open the valve 132 to admit air from a source to the pipe 133 and its connections. Also, the impulse thru 118 attracts armature 134 to open springs 135 and 136. The connections of relay 118 are such that it is a "slow" relay as far as armature 131 is concerned, and a "fast" relay as far as armature 134 is concerned.

When armature 131 closed springs 128—129 as a result of the impulse thru relay 118 previously described, a circuit was completed as follows: X'—130—129—128—137—138—139—140—141—142—143 (142 and 143 are closed in normal position)—144—X'. The current thru 139 attracts armature 145 which opens valve 146 to admit compressed air to pipe 147 and connections.

Air admitted to pipe 147 flows to motor 148 which moves lever 149 to advance ratchet 150 and its connected insulated wipers 107 and 151 from normal to mid-position. Air also flows to motor 152, but this does not operate until an escapement 90 permits it to operate as will be described.

The operations so far described all result automatically from the closure of a circuit at the calling station by the subscriber removing his receiver. The above statement of operations is a condensed one. In still more condensed form:—The subscriber removes his receiver, and this initiates automatic operations which connects him to the relay 118 of an idle selector, the relay becoming energized from the common battery in the central office thru the sub-station. The next thing done by the subscriber after removing his receiver is to operate the dial of his calling device. In doing this he breaks and remakes the circuit thru relay 118 one or more times with a degree of rapidity which operates the armature 134 but does not give time for the armature 131 to operate. The magnet 100 on the line switch, and magnet 139 on the selector, are "slow" magnets for the same reason that magnet 76 is slow.

Upon first closure of springs 135 and 136, a current flows:—X'—135—136—153—154—151—155—156—157—137—128—129—X'. Impulses thru magnet 157 operate escape wheel 158 and permit motor 152 to move the selector wipers step by step to successive rows of contacts.

At the first movement of the wipers to the right, the support 159 passes from under spring 142 so as to break the circuit for magnet 139, but the ratchet wheel 158 vibrates spring 142 in unison with the dial operations so that the armature 145 for magnet 139 does not have time to fall back. But at the end of the first dial operation the spring 142 rests at the position shown and this definitely breaks the circuit for magnet 130.

139. Thereupon armature 145 falls back and valve 146 closes. This shuts air from motor 148 whereupon lever 149 falls back and opens valve 160. This admits air to 5 motor 161 which immediately moves the wipers upward on a trunk hunting movement.

When an idle trunk is found a circuit is completed as follows:—X'—130—129—128—10 137—138—139—140—162—163—164—165—166—167—X². This operates magnet 139 to open valve 146 and permit air to flow again to motor 148 which advances wipers 107 and 151 to their final position,—that 15 shown in Fig. 7. In this movement, wiper 151 tilts lever 168 so as to permit the normally open valve 169 to close thus shutting off the supply of compressed air which flows thru valve 16 to motor 161. Pawls indicated 20 in Fig. 7 and described in my before mentioned application, Number 250,873, hold motor 161 from falling back when the air is shut off by valve 169.

It was previously described how the operation of the line switch extended the subscriber's line to the wipers 117 and 121 in engagement with wires 122 and 123. The last described movement of the wipers 15' and 107 extend these connections to found 25 trunks and battery as follows: 122—170—151—171—172—173—179—180—181—X²; and 123—175—107—176—177—178—174—166—167—X².

The relay 180 is like the relay 118 and has 30 a "fast" armature 182 and a "slow" armature 183 which acts to open the valve 184 to permit compressed air to flow from the general supply pipe 185 to the local supply pipe 78. The relay 180 is controlled from the local station in the same way as relay 118.

When the connector is in normal position the springs 164 and 165 are closed by a projection 186 carried by motor 19. In Fig. 1 this projection is shown attached to cross-head 83. On frame 17 is a pin 187 which 45 normally engages spring 196 so as to hold it in the position shown in Fig. 1, but when the motor 19 moves the frame 17 to the right, the pin 187 permits spring 196 to fall to the position shown in Fig. 8.

When the relay 180 is connected to the subscriber's line in the manner described, it is energized from the battery by way of the local station. This attracts armature 183 55 to open valve 184 so that compressed air may flow to valves 69 and 77 preparatory to future operations. Armature 183 also closed springs 188 and 189, whereupon an impulse flows:—X²—181—188—189—190—191—76—192—wiper 193—194—195—196—197—198—166—167—X².

As a result magnet 76 attracts armature 81 to open valve 77 so that compressed air may flow thru the connecting pipes to 65 motors 19 and 58. The motor 58 lifts lever 59

to open the adjacent contact springs and to prepare pawl 66 for subsequent movement of ratchet wheel 57. The air acting on motor 19 moves it far enough to permit springs 164 and 165 to open but not far 70 enough to permit spring 196 to move away from spring 197. This last occurs only when magnet 28 operates its escapement as before described.

When the subscriber next operates his 75 calling device he breaks and remakes the circuit thru relay 180 whereupon an impulse flows:—X²—181—188—189—190—wiper 199—200—201—28—202—203—204—166—167—X². 80

This operates the escapement to permit motor 19 to move the wipers 86 to 89 to the right, and is repeated a desired number of times to bring those wipers under the desired vertical row of contacts. Upon the 85 first movement of the escapement for motor 19, the pin 187 leaves spring 196 and said spring drops to spring 205, whereupon the steady current before described as passing thru magnet 76 is changed to a pulsating 90 current as follows:—X²—181—188—189—190—191—76—192—193—194—195—196—205—202—203—204—166—167—X².

When the subscriber pauses in the operation of his dial, springs 203 and 204 remain 95 open with the result that the circuit is broken for magnets 28 and 76. Breaking for 28 simply arrests the forward movement of motor 19 and leaves wipers 86 to 89 under the desired row of contacts. Breaking the circuit for magnet 76 permits valve 77 to close and shut the air from motors 19 and 58. Pawls previously described hold motor 19 so that nothing happens at this point, but motor 58 falls back and the wipers 193 and 199 carried by ratchet wheel 57 are advanced to their mid-position. In moving, the ratchet wheel 57 tilts lever 71 to open valve 69 and permit air to flow thru pipe 18 to motor 15. 100

When the subscriber operates his dial again to break and remake the circuit thru relay 180, impulses flow as follows:—X²—181—188—189—190—wiper 199—206—207—36—202—203—204—166—167—X². 110

Magnet 36 is the vertical escape magnet which operates in unison with relay 180 and permits the motor 15 to move upward step by step. Magnet 36 also has a projection 208 on its armature, which projection closes springs 210 and 211 to send a pulsating current thru magnet 76 as follows:—X²—181—188—189—190—191—76—192—209—210—211—212—166—167—X². This circuit thru magnet 76 again opens valve 77 to again 115 operate motor 58 and lift lever 59. At the end of the impulses sent by the subscriber, the circuit is again broken thru magnet 76 and lever 59 again falls back. This advances wipers 193 and 199 to their final position, 120

125 130

which is that shown in Fig. 8. In this final position a pin 213 on ratchet wheel 57 closes adjacent springs 214 and 215.

It was previously described that the selector connected the subscriber's line to wires 173 and 178. The final movement of the connector extends these connections to the wipers 88 and 89 as follows:—173—179—220—221—221a—88; and 178—216—217—10 218—219—89.

At the left in Fig. 9 is a condensed diagram of the connector A which the calling subscriber is assumed to be using and get connection with some other subscriber. 15 This connector is shown in its normal position. At the right in Fig. 9 is shown another connector B which some other subscriber has moved to find connection with some called subscriber. The purpose of Fig. 20 9 is to show what happens if the calling subscriber tries to get connection to the subscriber called by the connector B to the right. Assume that the wipers 193 and 199 of connector A are in their mid-position, and that 25 the calling subscriber attempts to stop his switch in connection with the bank contacts shown, which bank contacts correspond to the bank contacts engaged by switch B to the right. Under these conditions a current 30 will flow as follows: X—181—to 188 of switch A—189—190—191—76—192—193—222—223—87—224—225 to 224 of switch B—87—223—226—215—214—227—167—X.

With switch A stopping in this position a 35 steady current is kept on magnet 76 which holds valve 77 open and keeps air on motor 58. As wipers 193 and 199 move to final position, and wires 173 and 178 are connected to wipers 88 and 89 only when motor 58 40 falls back, it will be seen that no connection will be made to a subscriber to be called if that subscriber has already been called by and is in connection with some other party.

It was previously described how the calling 45 subscriber placed his connector on the contact terminals of a subscriber to be called when no other person is in connection with that subscriber. This position is shown in Fig. 8. Upon the stoppage of the connector 50 in desired position a circuit is completed as follows: X—181—188—189—190—199—228—86—229 thru Fig. 7 to 100 in the line switch to the right in Fig. 6—99—X.

The impulse thru the magnet 100 of the 55 called line switch produces the same result as before described for the line switch to the left. This is opening valve 111 to admit air to motors 112 and 113. Motor 112 permits pawl 230 to fall in over a collar 231 on motor 98 from moving from normal position if 60 air should be admitted to motor 98 under conditions to be hereinafter explained. The motor 112 has a check valve at 232 which acts to make this motor "slow" on release.

65 Motor 113 of called switch shifts the ad-

jacent contact springs as was described for the calling switch. This shift connects the wires leading to the local station to the wipers of the line switch. In this case the wipers are in contact with only battery 70 connections, but there are branches tapped from the wiper connections, and these branches are the normal wires whose terminals were connected to by the connector. Referring to Fig. 8 it will be seen 75 that the wiper 88 is in contact with the terminal of wire 233 which may be traced thru Fig. 7 to Fig. 6 where it is found to be an extension of wire 120 described in connection with the other line switch as being connected to the local station. In the same way wiper 89 of the connector is in contact with the terminal of wire 234 which may be traced in the same way to the called line switch where it is found to be an extension of wire 116 which is connected to the local station. 80 85

What has been so far described shows the calling station connected to a called station. There will, of course, be signaling apparatus for calling the called subscriber, but for simplicity of showing that is omitted from the present application and will be shown in another case. It will simply be assumed 90 that the subscriber has been called, has 95 talked and has come to the time of hanging up his receiver.

If the called subscriber hangs up first, then there are no complications. But if the calling subscriber hangs up first, he breaks 100 the circuit he made for magnet 100 of the called line switch and this lets air escape from motor 113. The result is that the adjacent contact springs fall back to normal position and a circuit is completed for magnet 96 of the called switch because the called subscriber still has his receiver off its hook. This opens valve 97 to admit air to motor 98, but motor 112 is "slow" to exhaust, and pawl 230 is over collar 231 and the motor 110 105 110 cannot move on a trunk hunting operation. By observing the relationship of the pivot to pawl 230 to the direction of strain upon that pawl when the air is acting on motor 98 it will be seen that the arrangement is a self-locking one. The motor 98 cannot move upward no matter how long the called subscriber may keep his receiver off its hook. But when he hangs up the 115 120 circuits are all broken and air is exhausted from all motors.

During talking the relays 118 and 180 are bridged on the talking circuit and are energized from battery by way of the calling station. When the calling subscriber hangs up his receiver he breaks this circuit and relays 118 and 180 resume normal position. When relay 118 is de-energized, armature 131 falls back and permits springs 128 and 129 to separate. As these springs are in the 125 130

circuit for magnet 100 that magnet releases valve 111 so that air is shut off from motors 112 and 113. When motor 113 falls back, the holding pawl 114 is withdrawn and 5 motor 98 falls back.

Breaking the circuit thru relay 180 on the connector permits valve 184 to close and shut the air supply from pipe 78. A branch 235 leads from pipe 78 to motor 40, and 10 when valve 184 was first opened air flowed to this motor to permit the holding pawls 45 and 50 to engage their ratchets. When valve 184 closes motor 40 falls back and 15 engages these pawls. Releasing pawl 45 permits the vertical motor 15 to fall back, and as this motor reaches its normal position the arm 55 on shaft 35 strikes the extension 54 of pawl 53 so as to release this pawl and permit the horizontal motor 19 to 20 return to its normal position.

The release for the selector of Fig. 7 is very similar to that just described for the connector. It has been given in detail in my application previously mentioned.

25 Reviewing the operation in condensed form, the calling subscriber removes his receiver and thereby closes a circuit for the magnet 96 on his individual line switch. This admits air to motor 98 which immediately moves its wipers upward. When these find an idle trunk a circuit is completed for the magnet 100 which throws in the stopping pawl 110, and opens the valve 111 so as to admit air to motor 113. The 30 motor 113 throws in the holding pawl 114, and shifts contact springs so as to connect the station wires to the wipers and thru them to battery and relay 118 on idle selector.

35 Relay 118 opens valve 132 to admit air to the local pipe system, and closes a circuit for magnet 139 which in turn opens valve 146 to admit air to motors 148 and 152. Up to this point all operations automatically result from lifting the receiver 40 from its hook.

When the subscriber first operates his dial the selector of Fig. 7 moves to the right a number of steps which corresponds 50 to the number indicated by the dial movement. The impulses for this are relayed to magnet 157 which operates an escapement for this purpose. When the first dial movement ceases the consequent pause in the flow 55 of impulses brings about, thru intermediate operations, an opening of valve 160 to admit air to motor 161. This motor carries its wipers upward and when these wipers come to the terminals of an idle trunk, the 60 selector is automatically stopped and the subscriber's line is extended to the relay 180 on the connector.

The next two operations of the dial cause the connector to move step by step first 65 horizontally and then vertically to the ter-

70 minals of the line leading to the line switch belonging to the subscriber to be called. When this point is reached, the connector automatically connects the calling line to the found terminals. If, however, the subscriber to be called has already been called by some other person, then the connector does not extend the calling line. In exchanges as ordinarily made, the connector extends the calling line to the terminals found and then breaks the connection if the called subscriber is previously busy. In the present case, if the subscriber to be called is previously called, then the connector never makes the movement necessary 75 to extend the calling line.

When the connector extends the calling line to the terminals of a called subscriber it closes a circuit which causes an operation of the line switch belonging to the called subscriber if such line switch is in its normal position. If, however, the line switch has been moved to make a call, then the contact springs 236 and 237 at the line 80 switch are open and no circuit can be completed to magnet 100 of the called line switch. It should be observed that the magnet 100 of the calling switch acts as a trunk selector, and magnet 100 of the called switch acts as a connector by connecting the subscriber's line to his normal wires and as a cut out by disconnecting the magnet 96 from the subscriber's line.

85 In normal position the line switch wipers 117 and 121 engage contacts 238 and 239 which are connected thru resistances to a battery. In the normal position of motor 113, the wipers 117 and 121 are disconnected at springs 115 and 119, and the battery is 90 not employed. But when the line switch is called the wipers 117 and 121 are connected to the local station and the connected battery serves for talking purposes. The 95 calling station is connected to battery X' for talking purposes.

100 What I claim is:

1. In a telephone exchange, a line leading from a local station to wipers such as 88 and 89, pneumatic motors for moving 105 said wipers successively in directions perpendicular to each other, other wipers such as 193 and 199 serving in the electrical control of said motors, and a special motor serving to shift the last mentioned wipers and to temporarily break the connection between the local station and the first mentioned wipers.

110 2. In a telephone exchange, a line leading from a local station to wipers on a connector, a line leading from a second local station to a line switch, a line leading from contact points on the connector to the line switch but normally disconnected from the line leading from the local station to the line switch, and means operating thru the con- 115

nection and involving a pneumatic device on the line switch for connecting together the two lines leading to the line switch.

3. In a telephone exchange, two line switches connected to corresponding local stations, connections extending from wipers on one line switch to normal wires on the other, and locking devices on the second line switch and controlled over said connections by a magnet and pneumatic device on the switch.

4. In a telephone exchange, a line switch having wipers for talking connections, a line leading from the line switch to a local station but normally disconnected from said wipers, means by which the line is connected to the wipers for any talking circuit extending to said local station as a called station, and battery connections engaged by said wipers when in normal position but disengaged therefrom when the wipers have been moved.

5. In a telephone exchange, a line switch arranged to make connections for talking purposes either as a calling or a called medium, a line extending from said switch to a local station, and battery connections connected to said line at the line switch when said switch is a called medium but disconnected therefrom by the movement of the line switch when said switch is a calling medium.

6. In a connector switch, wipers for making telephonic connections, pneumatic motors serving to move said wipers in directions perpendicular to each other, an escapement for each motor, a relay arranged to control the operations of said escapements successively so as to permit said motors to move said wipers successively, and means for controlling said relay from a distant station.

7. In a switching mechanism having wipers, a pneumatic motor for moving the wipers in one direction, an escapement for permitting the motor to advance step by step, a second pneumatic motor for moving the wipers in a second direction, an escapement for permitting the second motor to advance step by step, and electrical controlling means for causing the step by step movements in the second direction to follow those in the first direction.

8. A pair of wipers, a pneumatic motor, an escapement for permitting the motor to move the wipers step by step, a second pneumatic motor for moving the wipers in a second direction, a second escapement for permitting the second motor to advance step by step, and electro-magnetic means for controlling said escapements in succession.

9. In an automatic telephone exchange having line switches and selectors, a pneumatic motor on each selector for moving it, a source of compressed air, and means by

which upon a subscriber closing electrical connection at his local station the associated line switch will automatically find an idle selector and compressed air will be automatically admitted to the motor on the found selector.

10. In an automatic telephone exchange in which calls from a local station pass through primary and secondary switches, a pneumatic motor on each secondary switch for moving it, a source of compressed air, and automatic means for admitting compressed air to the motor of a secondary switch upon a subscriber closing an electrical connection at his local station.

11. In a telephone exchange, a line leading from a local station through successive switches to a pair of wipers on a connector switch, pneumatic motors for moving said wipers step by step over a series of contacts to a desired position, and means for breaking the connection between the station and said wipers during the making of such movement.

12. In a telephone exchange, a calling and a called station, a line leading from a calling station to a pair of wipers on a connector switch, pneumatic motors for moving said wipers step by step into engagement with the contacts of the called station, other wipers serving in the control of said motors, a special motor which breaks the connection between the calling station and said first mentioned wipers when in operated position and which operates said other wipers when returning to normal position, and means controlled by the busy condition of the called station for maintaining said special motor in operated position.

13. In a telephone exchange, a calling and called line, a plurality of pneumatically operated switches and a pneumatic connector for completing connections between the calling and the called line, a pneumatic side switch in said connector, and means in said connector for controlling said side switch to disconnect said calling line from said called line when said called line is busy.

14. In a telephone exchange, a calling and a called line, a plurality of pneumatically operated switches and a pneumatic connector for completing connections between the calling and the called line, a pneumatic side switch in said connector, and means in said connector for preventing said side switch to reach final position and for controlling said side switch to break the connection between the calling and called lines when said called line is busy.

15. In a telephone exchange a calling and a called line, electrically controlled and pneumatically operated line switches, selector and connector switches for completing a connection between the calling and the called lines, means for operating said

- switches to establish a connection between a calling and a called line, and a pneumatic side switch in said connector for preventing the establishment of said connection when 5 the called line is busy.
16. In a telephone system, a calling and called subscriber each having pneumatic line switches individual thereto, pneumatic selector and connector switches, means controlled by the calling subscriber for actuating his individual line switch to seize an idle selector switch, and means controlled by the calling subscriber to actuate said selector switch to seize an idle connector switch and 10 then to actuate said connector to seize said called subscriber's individual line switch.
17. In a telephone system, a calling and a called subscriber each having pneumatic line switches individual thereto, pneumatic selector and connector switches, means controlled by the calling subscriber for actuating his individual line switch to seize an idle selector switch, means controlled by the calling subscriber to actuate said selector switch 15 20 to seize an idle connector switch and then to actuate said connector to seize said called subscriber's individual line switch, and means for establishing talking circuits between said subscribers.
18. In a telephone exchange, two line switches connected to corresponding local stations, connections extending from one of said local stations through the wipers on one of said line switches to normal wires on the 25 other, locking devices on the second line switch controlled over said connections by a magnet and pneumatic device on said second switch, and means for extending said connections to include said second station.
19. In a telephone exchange, a line switch having wipers for talking connections, a line leading from the line switch to a local station but normally disconnected from said wipers, a pneumatic motor for connecting 30 said line to said wipers, and battery connections for talking purposes engaged by said wipers when in normal position but disengaged therefrom when said wipers have 35 been moved.
20. In a telephone exchange having line switches and selectors, the combination with a pneumatic motor and a starting magnet on each line switch and on each selector, and trunk connections between line switches and selectors, of means by which upon closing a 40 circuit for the starting magnet on a line switch the associated pneumatic motor and the starting magnet on the selector with its associated pneumatic motor will all be automatically operated. 50
21. In an automatic trunk selecting system having primary and secondary mechanisms, a starting magnet and a pneumatic device on each primary mechanism, a pneumatic device on each secondary mechanism, and intermediate connections so arranged that upon a circuit being closed through the starting magnet of the primary mechanism power will be automatically applied to the pneumatic device on the primary mechanism 55 and then automatically applied to the pneumatic device on the secondary mechanism. 65
22. In a telephone exchange having line switches and selectors, the combination with a pneumatic motor and a starting magnet on each line switch and on each selector, and trunk connections between line switches and selectors, of means by which upon closing a 70 circuit for the starting magnet on a line switch the associated pneumatic motor and the starting magnet on the selector with its associated pneumatic motor will all be automatically operated, of means for breaking the circuit of the starting magnet of the line switch when the line switch seizes said selector, and of means for holding said line switch in operated position after the circuit of the starting magnet of the line switch 75 has been broken. 80
23. In a switching mechanism, the combination with a carriage, motors for moving said carriage in different directions, means for operating said motors, of escapements for restraining said motors from operation, a magnet, and means controlled through said 90 magnet for operating said escapements. 95

FRANK A. LUNDQUIST.
